3 SHEETS—SHEET 3.

UNITED STATES PATENT OFFICE.

JOHN F. SHELTON, OF FORT WORTH, TEXAS.

WIRE-WORKING MACHINE.

1,325,047.

Specification of Letters Patent. Patented Dec. 16, 1919.

Application filed March 6, 1919. Serial No. 281,002.

To all whom it may concern:

Be it known that I, JOHN F. SHELTON, a citizen of the United States of America, residing at Fort Worth, in the county of 5 Tarrant and State of Texas, have invented certain new and useful Improvements in Wire-Working Machines, of which the following is a specification.

My invention relates to wire working machines and more particularly to forming hangers for coats, trousers, and other clothing; and the object is to provide a machine which is relatively inexpensive and which can be operated with rapidity and accuracy 15 with little power and which will be highly efficient in turning out great quantities of hangers in short time. Other objects and advantages will be fully explained in the following description and the invention will 20 be more particularly pointed out in the claims.

Reference is had to the accompanying drawings which form a part of this application.

25 Figure 1 is a front side elevation of the machine. Fig. 2 is a plan view of the same. Fig. 3 is an end elevation of the same. Fig. 4 is a detail view of the hook-forming mechanism. Fig. 5 is a view of a hanger made 30 on the machine herein described. Fig. 6 is a detail view of one of the throw rods. Fig. 7 is a side elevation of one of the body formers. Figs. 8, 9, and 10 are detail views of the cam lock and release. Figs. 11 and 35 12 are detail views of the twisting die.

Similar characters of reference are used to indicate the same parts throughout the several views.

The machine is provided with a rectangular frame 1 supported by upright posts 2 which may be of angle iron or channel iron. The machine is provided with two cog wheels 3 which are provided with shafts 4 which are journaled in a platform frame 40 piece 5 which is rigid with the machine frame. The shafts 4 project above the cog wheels 3 and constitute parts of the forming mechanism, serving to make the short bends in the hangers. The cog wheels 3 45 carry the two main forming elements 6 which are rigid therewith. During the operation of forming a hanger, the cog wheels 3 are driven to bring the formers 6 around to the dotted outline positions shown 50 in Fig. 2. Brackets 7 and 8 are provided for holding the wires. These brackets are

mounted on the platform 5. The bracket 7 has an upright member 9 which serves as a gage for placing the wires on the wheels 3. The end of the wire 13 is placed 60 on the bracket 7 and against the upright member 9. This bracket 7 is so positioned that a greater portion of the wire 13 will be to the right of the plate 14, as shown in Fig. 2, and the portion of the wire to the right of the plate 14 is sufficiently greater than the portion toward the member 9 to form a shank and a hook on the shank. In such position, one end will project beyond the other when the ends are brought together. This is necessary so that the shank of the hanger will be at the right place when formed. A platform or holder 10 is positioned just above the wheels 3 for the wires, and this holder is carried by a bracket 11 70 which is attached to a bar 12 which is attached to the machine frame. When the wheels 3 are rotated, the ends of the wire 13 are bent about the shafts 4 by the formers 6 and brought against a former plate 14 75 and pressed firmly against this plate. This is the first step in the process of forming the hanger. The wheels 3 are driven by a motor 15 which is provided with a pulley 16 which drives a belt 17. The belt drives a pulley 18 which is integral with the balance wheel 19. Pulley 18 drives shaft 20 which carries and drives a pinion 21. The pinion 21 drives a cog wheel 22 which is rigid with shaft 23 and drives this shaft. 80 The shaft 23 runs continuously during operation. Means are connected with this shaft and with the wheels 3 for driving the wheels 3 intermittently. A pulley 24 is made rigid with one of the shafts 4 and a strap belt 85 25 is attached to the pulley 24 at one end and then run over a pulley 26 and attached to a lever 27 which is fulcrumed on the frame at 28. The lever 27 is actuated by a cam 29 which is loosely mounted on the 90 shaft 23. The cam 29 is locked to the shaft 23 for driving purposes by a collar 30 and a plunger pin 31. The cam 29 has a hub 32, and a recess 33 is cored out longitudinally in the hub, and a slot 34 is made in 95 the periphery of the hub (see Fig. 9). The plunger pin 31 moves longitudinally in the recess 33. A lug 35 is integral with the pin 31 and projects through the slot 34. A spiral spring 36 tends to keep the pin 31 100 thrust toward the collar 30. The collar 30 has a number of recesses 37 adapted to re-

ceive the pin 31. Unless the pin 31 is held out of the collar 30, the cam 29 would turn continually with the collar 30. In order to withdraw the pin 31 from the collar 30 a beveled trip or releasing device 38 bears against the hub 32. As the hub 32 turns toward the trip 38, the lug 35 will strike the trip or cam release 38 and the pin 31 will be forced back toward the cam 29 10 against the tension of spring 36 and the pin 31 will be withdrawn from the collar 30 so that the cam 29 can be released from the shaft 23. The lug 35 will strike the stop 39 and the cam 29 will be held stationary until the stop 39 is withdrawn from the lug 35. At the moment when the stop 39 is withdrawn from the lug 35, the spring 36 will instantly thrust the pin 31 into the collar 30 so that the cam 29 will be driven 20 with the shaft 23 and collar 30. The stop 39 is slidably mounted in a bracket or keeper 40 which is attached to the support 41 which is bolted to the machine frame. The stop is actuated by compound levers 42 25 and 43. The lever 42 is fulcrumed to the bar 12 at 44 and the lever 43 is pivotally connected to the lever 42 and fulcrumed on the bar 45 at 46. The lever 43 is held in position to press the stop 39 against the hub 32 by means of a spring 47 which is attached to a frame piece 1 and to the lever 42. The lever 42 is manually operated to 30 actuate the lever 43. As soon as the cam 29 is released it will commence revolving 35 and will strike the lever 27 and bear this lever down so that the wheel 26 will be turned and the gear wheels 3 will be rotated through the gearing above described.

through the gearing above described.

The operation of the parts above described may be briefly described. The shafts 20 and 23 run continually while the motor 15 is connected to a supply source of electricity. A wire 13 is put in place as shown in Fig. 1. The levers 42 and 43 are actuated to release the cam 29 which commences to turn for actuating the lever 27 for actuating the gearing to turn the wheels 3. The wheels 3 by means of the formers 6 bend the wire to the dotted outline position and by the time this is accomplished, the cam 29 has revolved once and is released from driving position by the stop 39.

Means are provided for restoring the wheels 3 to starting position. The wheels 55 3 are locked in position at points where they have brought the formers 6 to dotted outline. A lock 50 is attached to the bottom of one wheel 3 and is adapted to catch on a stop 51 which is adjustably attached to the 60 frame piece 1. Means are provided for releasing the catch 50 so that the wheels 3 can go back to starting position. A lever 52 is fulcrumed on the vertical bar 53 and carries a push rod 54 which rests against the bottom 65 of the latch 50. A link bar 55 is pivotally

connected to the lever 52 and depends therefrom and hangs down in a guide casing 56 and a pedal 57 is formed on the bottom. The operator simply presses on the pedal 57 for releasing the wheels 3. One wheel 3 drives the other. A strap belt 58 runs over a pulley 59 and then to and about pulley 24, above described. The belt 58 is supported on pulley 24 by the flange 58'. A weight 60 is attached to the other end of the belt 58. As soon as the latch 50 is released from the stop 51, the weight 60 will automatically restore the wheels 3 to starting position. 70 75

A rack 61 is provided on the back part of the machine for supporting a supply of rods or wires to be formed into hangers and a rod 62 is mounted on brackets above the machine to support the completed hangers. 80

Means are provided for twisting the ends of the wire together after they have been 85 pressed against the plate 14. The plate 14 is pivotally mounted by a pivot bolt 14' and is swung backwardly out of the way of the twisting device. The twisting device consists of a hollow shaft 63 which is 90 journaled in bearings attached to the upright frame piece 2. This shaft is thrust manually on the ends of the wire and then twisted by means of a crank 64. The shaft 63 is provided with a die 82 which is 95 screwed into the end of the shaft 63. The die has a widened opening 83 for receiving the two ends of the wire for forming a twist in the wire.

After the ends of the wire are twisted together, a hook is formed of one end of the wire which is longer than the other end. For this purpose a die 65 is provided and mounted on a plate 66 which is hinged to a bracket 67. A coöperating die member 68 is movable in a slot 69 in plate 66. The die member 68 has a shank 70 which projects down into a holder 71 loosely and the holder 71 is actuated by a bar 72 which is pivotally connected to a lever 73. The holder 71 slides on the frame piece 1. The upright support 2 is braced to the machine frame by braces 74. The plate 66 is swung up to horizontal position. The long end of the wire lies across the curved cavity in the die 65. The coöperating die member 68 is then forced against the wire by means of the

forced against the wire by means of the lever 73 and the wire is partly curved. A bending device, consisting of a lever 75 which carries a hook member 76, is then operated to force the end of the wire about the die member 68. The lever 75 is pivotally mounted on the die member 65 and swings in a plane parallel to the plate 66 between stops 77 and 78, and the hook 76 depends from the lever 75 to engage the portion of the wire which is not bent by the die members 65 and 68 and completes the bending of the wire on member 68 to make the hook. Stops 77 and 78 limit the movement of the lever 75.

lever 75. The lever 73 and the bar 72 are also used to lift the plate 66 up from the position shown in Fig. 4 to horizontal position for forming the hook on the hanger. The spring 79 normally holds the hook-forming devices down to the position illustrated in Fig. 4. The throw-rod 72 is adapted to rest on and slide on the cross-pin 86 used as a fulcrum.

When a hanger is finished, it is shoved up from its position for removal by a push rod 80 which carries a lug 81 for lifting the hanger off the shafts 4. This is done at the same time the pedal 57 is pressed down for releasing the wheels 3 by releasing the latch or hook 50 from the stop 51. The lever 52 lifts the push rod 80 at the same time it lifts the push-rod 54.

A guide 84 is provided for the lever 27. The wheel or pulley 26 is provided with a shaft which is journaled in hanger bearings 85 and a bridle-shaped guide 84 is attached to the bearings 85 so that the strap belt 25 will not leave the pulley 26. The guide 84 simply prevents lateral motion of the lever 27 so that when this lever is actuated it will move in true vertical direction and so hold the belt 25 in line with pulley 26.

What I claim is:—

1. A wire forming machine comprising a frame, a pair of horizontally disposed wheels provided with shafts journaled in said machine frame and projecting above the plane of the wheels, means for supporting a wire above and in close proximity to the plane of said wheels, a centering plate pivotally mounted and adapted to lie in the path of the wire under operation, means for positioning the wire on said supporting means with a greater length of the wire on one side of said centering plate than on the other side of said plate, formers carried by said wheels and adapted to bend a wire about said shafts and to press the ends thereof against said plate, means for rotating said wheels, and means for twisting the ends of the wire together after removal of said plate.

2. A wire forming machine comprising a frame, a pair of horizontally disposed wheels provided with shafts journaled in said frame and projecting above the plane of the wheels, means for supporting a wire above and in close proximity to the plane of said wheels, a centering plate pivotally mounted, formers rigid with said wheels for bending the wire about said shafts and pressing the same against said plate, a manually operated shaft, and a die carried thereby for twisting the ends of said wire together after removal of said plate.

3. A wire forming machine comprising a frame, a pair of horizontally disposed wheels provided with shafts journaled in said frame and projecting above the plane of the wheels, means for rotating said wheels, means for

supporting a wire above and in close proximity to the plane of said wheels, a centering forming plate pivotally mounted, formers carried by said wheels for bending the wire about said shafts and pressing the same against said plate for forming a shank of the end portions of said wire, a manually operated shaft, and a die detachably connected to said shaft for engaging the ends of the wire and twisting the same together after removal of said plate.

4. A wire forming machine comprising a frame, a pair of horizontally disposed wheels provided with shafts journaled in said frame and projecting above the plane of said wheels, means for rotating said wheels, means for supporting a wire above and in close proximity to said wheels and means cooperating with the supporting means for gaging the wire to project one beyond the other when the ends are brought together, a centering and forming plate pivotally mounted, formers carried by said wheels for bending the wire about said shafts and against said plate for bringing the end portions of the wire close to and parallel to each other, a manually operated shaft, and a die detachably connected to said shaft for engaging the ends of said wire and twisting the same together.

5. A wire forming machine comprising a frame, a pair of horizontally disposed wheels provided with shafts journaled in said frame and projecting above the plane of said wheels, means for rotating said wheels periodically, means for supporting a wire above and in close proximity to said wheels, a shank forming plate pivotally mounted on said frame, formers carried by said wheels for bending the wire about said shafts and against said plate, means for twisting the ends of the wire together after removal of said plate, and hook forming devices for forming a hook on one end portion of the wire after the wire has been twisted together.

6. A wire working machine having means for forming a loop of a wire and a shank composed of parallel portions of the wire, gaging means for positioning the wire to make one end project beyond the other, means for twisting the end portions together, and means for forming a hook on the projecting end portion of the wire, including concave and convex die members for partly forming the hook and a lever carrying a hook for coöperating with said convex die member for completing the hook.

7. A wire working machine having means for forming a loop of a wire and a shank composed of parallel portions of the wire, gaging means for positioning the wire to make one end project beyond the other, means for twisting the shank portions together, and means for forming a hook of the projecting end consisting of one concave die

- member and a cylindrical die member movable toward the concave member for bending the wire between the two members.
8. A wire working machine having means for forming a loop of a wire and a shank composed of parallel portions of the wire, gaging means for positioning the wire to make one end of the parallel portions project beyond the other, means for twisting the shank portions together, and means for forming a hook of the projecting end portion consisting of a concave die member and a cylindrical die member movable relative to said concave member, means for moving said cylindrical member to press the wire into said concave member, and a lever carrying a former for completing the hook about said cylindrical member.
9. A wire working machine having means for forming a loop of a wire and a shank composed of parallel portions of the wire, gaging means for positioning the wire prior to the forming process to cause one end of the parallel portion to project beyond the other, and means for forming a hook of said projecting portion consisting of a concave die member and a cylindrical die member movable relative to said concave die member, means for forcing said cylindrical member to press the wire into said concave member, and a lever carrying a forming device for completing the hook about said cylindrical die member.
10. A wire working machine having a frame, means for forming a loop in a wire and a shank composed of parallel portions of the wire, gaging means for positioning the wire on said frame prior to the forming process to cause one end of the wire to project beyond the other during the forming process, means for twisting said parallel portions together, and means for forming a hook of said projecting end portion consisting of a plate hingedly connected to said frame, a concave die member mounted on said plate, a cylindrical die member loosely connected to said plate and movable relative to said concave member, a lever and a shifting bar on said frame for forcing said cylindrical member to press the projecting end of the wire into said concave member, and a lever fulcrumed on said frame and provided with a former for completing the hook about said cylindrical member.
11. A wire working machine having a frame, a pair of horizontally disposed wheels provided with shafts journaled in said frame and projecting above the plane of said wheels, means for supporting a wire above and in close proximity to said wheels, a centering forming plate pivotally mounted on said frame, formers carried by said wheels and adapted to bend the wire about said shafts and against said plate to form a shank of the end portions of said wire, and means for driving said wheels periodically consisting of cogs on said wheels whereby one wheel drives the other, a shaft continually revolving during operation, a cam on said shaft operatively connected to said driving wheel for driving the same, means for locking said cam to said shaft for driving purposes, and means for automatically detaching said cam from said shaft and stopping the revolving thereof.
12. A wire working machine having a frame, a pair of horizontally disposed wheels provided with shafts journaled in said frame and projecting above the plane of the wheels, means for supporting a wire above and in close proximity to said wheels, a centering forming plate mounted on said frame, formers carried by said wheels and adapted to bend a wire about said shafts and against said plate to form a loop with a shank thereon of said wire, means for driving said wheels periodically consisting of cogs on said wheels whereby one wheel drives the other, a driven shaft continually revolving during operation, a cam loosely mounted on said shaft and provided with operative connections with said driving shaft for driving the same, means for locking said cam to said driven shaft for driving purposes, means for automatically detaching said cam from said driven shaft at the moment said formers press the wire against said plate, means for locking said cam in inoperative position, a lever for releasing the cam for driving purposes, said cam being automatically locked to said driven shaft as soon as released, and a weight operatively connected to said driving wheel for restoring said wheels to starting position.

In testimony whereof I set my hand this 21st day of May, 1918.

JOHN F. SHELTON.
